SMOKING STAND

William J. Campbell, Indianapolis, Ind., assignor
to Climax Machinery Company, Indianapolis,
Ind., a corporation of Indiana

Application November 16, 1934, Serial No. 753,260

16 Claims. (Cl. 131—51)

My invention relates to an improvement in stands, for example, in smoking stands. One object is the provision of a smoking stand which shall be efficient in use and stable, long lived, and difficult to break or tip over. Another object is the provision of a smoking stand with improved means for preventing the undesired and undesirable escape of smoke, vapors or the like from ashes and butts deposited within a smoking container. Another object is the provision of a smoking stand assembly which can be readily assembled. Another object is the provision of an improved removable receptacle for ashes, butts and the like. Another object is the provision of an improved housing and closure for such receptacle. Another object is the provision of a readily removable tray for glasses and the like. Another object is the provision of means for supporting simultaneously a plurality of trays upon a smoking stand. Other objects will appear from time to time in the course of the specification and claims.

I illustrate my invention more or less diagrammatically in the accompanying drawings, wherefore in—

Figure 1 is a side elevation with parts in section;

Figure 2 is a similar side elevation of the upper portion of my device with an additional tray added thereto;

Figure 3 is a section on the line 3—3 of Figure 2;

Figure 4 is a plan view; and

Figure 5 is a section on the line 5—5 of Figure 4.

Like parts are indicated by like symbols throughout the specification and drawings.

Referring to the drawings, I generally indicate a base which may include a heavy circumferential ridge 2, and an upstanding central portion or boss 3, closed by a top partition or wall 4. 5 generally indicates an upstanding support, herein shown, for purposes of illustration, as a single column, although more than one may be used. 6 indicates intermediate holding members which may be separately positioned but are here shown as separate elements but which may be formed integrally with a central column 5. 7 indicates a compression member in the form of a long bolt which is shown as aligned in perforated discs 8, 9, one position being shown at the bottom and the other at the top of the member 5. The upper end of the member 7 is screwthreaded as at 10 to conform to the screwthreads of a locking sleeve 11 which bears against the upper surface of the disc

9. 12 is a locking nut upon the lower screw-threading 13 at the bottom of the member 7, whereby the entire assembly may be locked firmly together. It will be observed that the upper end of the locking sleeve 11 is provided with a flange 14. The flanged sleeve passes through an aperture in a housing 15 and when the nut 12 is tightened up the bottom of this housing 15 is drawn down against the top of the central column 5 in such fashion that all the parts are solidly held together, the parts being centered by the fit of the rod or bolt 7 with the discs 8, 9.

The member 15 is provided with a plurality of circumferential ridges and angles 16 the purpose of which is primarily ornamental but which also serves to strengthen or reinforce the housing. A main upper circumferential flange 17 is employed which has the important function of acting as a tray support. 18 indicates a small tray having a central generally flat inner portion 19 and an outer downwardly turned flange 20. As the tray 18 is formed with an upwardly concave trough, as will be clear from Figure 5, its form is such as to prevent ready bending. The circumferential flange 20 serves as a species of reinforcement. The upward depression is convenient for receiving articles, cigarettes and the like, and keeping them from rolling off. The tray member 18 may be locked against the upper face of the flange 17, as by clamps or clips 21 through which may pass the lower portions of the bolts 22, the locking nuts 23 engaging the lower face of the locking clamps or clips. The heads of the bolts may pass through appropriate apertures in the flange 19 of the tray 18.

Resting upon the tray 18, or, if that tray is removed, upon the upper face of the flange 17, is a main tray structure 25, which includes also a surrounding upwardly and downwardly extending flange 26 and an inner collar 27. The flange 26 and the collar 27 serve as reinforcements for the flat tray 25, preventing its ready bending or deformation. The collar 27 is shown as extending upwardly a substantial distance, its upper edge abutting against the outer ring 31. This is advantageous as preventing tilting of the tray in relation to the stand. A very substantial weight may be placed upon one edge of the tray, without affecting the stability of the tray. In order to remove the tray it is necessary to lift it directly upwardly. In fact, it is practically impossible to remove the tray unless the tray is carefully lifted in horizontal position. This eliminates the tendency to spill articles upon the tray either by an unintended pressure downwardly at one

end of the tray at one edge thereof or by a careless lifting of the tray in a non-horizontal position.

39 generally indicates a closure cover for the 5 housing 15. It may include for example, a generally horizontal outer ring 31 with a downwardly extending flange 32 for centering it within the upper edge of the housing 15. This flat portion 31 may be channeled as at 33 for the easy laying 10 thereon of cigars, cigarettes or the like. 34 is illustrative of any suitable upward projection for receiving a box of matches or the like. 35 indicates a generally conic downwardly and inwardly extending flange which may, if desired, 15 be slightly rounded or arcuate in cross section, as it is in fact shown in Figure 5. This downward and inward extension 35 extends substantially below the level of the top flat portion 31. 36 is a handle, herein shown as generally arcuate, 20 which is secured to the portion 31 as by any suitable securing bolts 37. It is thereby removable from the member 30 but in use the two are intended to be employed together, there being no necessity for their separation. Extending downwardly from the central portion of the handle 36 is a pin 38 with a relatively sharp or conic point 39 at the bottom thereof and a screwthreaded portion 40 adjacent thereto, adapted to mesh 25 with the screwthreading of the upper portion of the locking sleeve 41. It will be understood that the pin 38 is readily rotatable in relation to the handle 36 and that when it is rotated into the locking position in which it is shown in Figure 30 5 the cover member 30 is drawn into snug locking engagement with the upper edge of the housing 15. The pin 38 is normally held against separation from the handle 36, as by a lower locking sleeve 41 and the upper knob 42, both of which 35 are mounted upon the upper screw threaded portion 43 of the pin 38. The set screw 44 prevents rotation of the knob 42 in relation to the pin 38 unless the set screw 44 is loosened to permit such rotation. Thus normally the cover 30, the handle 36, the pin 38, member 45, and the locking nut 40 45 42, form a single assembly which may be removed bodily from or applied bodily to the housing 15. Associated with the same assembly is a closure member generally indicated as 45 which includes 50 a hub or sleeve 46 engaging the pin 38 with a tapered cylindrical inner surface, the diameter of which increases downwardly from the upper edge, permitting the lower portion of the member 45 readily to tilt somewhat in relation to the vertical axis of the pin 38. The member 45 55 expands, downwardly from the central portion 46, into a species of bell 47 the outer face of which is tapered and generally conic. It terminates in a lower flange 48, having a downwardly and inwardly extending surface generally conic 60 in cross section. This outer surface of the flange 48 seats on the edge of an aperture in the lower portion of the extension 35 of the cover 30. Owing to the loose fit and the tapered inner surface of the hub 46 the bell portion 47 with its 65 lower face 48 can readily conform precisely to the lower edge of the member 35. In fact, as the parts wear, the opposed bearing faces tend to wear into a closer fit and the tightness of the fit therefore improves with use. The collar 27 of the tray is slightly conical, with the aperture slightly larger at the bottom where it makes contact with the part 15 and at the top contacts the flange 31 of the cover 30. This tapering two point 70 contact makes it easy to remove the tray or to 75

center it when replacing it in position on the stand and insures a snug fit.

Positioned in the housing 15 is the removable receptacle generally indicated as 50 the bottom of which has a central aperture 51 surrounded by and fitted to an upwardly extending sleeve 52. This sleeve 52 has an upper bell portion 53, for the easy penetration and guiding of the conic point 39 of the pin 38. This portion 53 has its upper edge well upwardly within the member 47, and well above the level of the bearing connection between the members 35 and 48. The tube 52 serves very readily as a guide for the pin 38 so that when the cover is being replaced after the emptying of the receptacle 50 of ashes or stubs, the pin 38 drops easily into place and all that the user has to do is to rotate the knob 42. It is impossible for the user to drop ashes or foreign material down the tube 52 and therefore the space outside of the receptacle 50 is kept clear of ashes or foreign material. It will be noted also that the upper edge of the receptacle 50 is at a higher level than the lower edge of the member 35, similarly preventing the escape of ashes down the outside of the receptacle 50. It will be also observed that the space between the member 35 and the upper edge of the housing 15 serves as a species of smoke or vapor trap, as does the inner portion of the cone 47 so that the tendency of any vapor or smoke to leak out about the edge of the cone 47 is reduced to a minimum.

As a further addition to or modification of my device I may, as shown in Figures 2 and 3, secure a supplemental tray to the handle 36. I may, for example, tap a hole in the top of the knob 42, as shown at 60 in Figure 3. This may be penetrated by a screwthreaded tap 61 with an upwardly extending screwthreaded or snug fitting portion 62 and an intermediate spacing or positioning disc 63. 64 generally indicates a tray with a circumferential flange 65 and a handle 66. The handle 66 is provided also with a snug fitting aperture 67 conforming to the upper member 62.

It will be realized that whereas I have described and shown a practical and operative device, nevertheless many changes may be made in the size, shape, number and disposition of parts without departing from the spirit of my invention. I therefore wish my description and drawings to be taken as in a broad sense illustrative and di-
agrammatic rather than as limiting me to my specific showing.

The use and operation of my invention are as follows:

In the use of my device the smoking stand 55 proper has an exceedingly efficient means for permitting the ready cleaning or dumping of the container 50, while preventing the escape of smoke or vapor during use. The stand may also be used to serve food and drinks. For example, the lower 60 tray 25, which is readily removable may be employed for glasses and drinks. The upper tray 64 may be employed for sandwiches and the like, or the two uses may be reversed. A number of 65 separate trays may be employed with a single stand, so that the user can remove one tray 25, with empty bottles and used glasses and immediately replace it with a fresh tray with new glasses, bottles and the like upon it. The supplemental tray 18 may be employed or removed at will. It 70 may be useful as a temporary receptacle when the tray 25 has been removed. Or the device may be employed without any trays, or with any single one of the above mentioned three trays or any combination thereof. 75

With reference, for example, to Figure 5, inasmuch as the vapor or smoke tends to rise, it will be clear that two smoke or vapor traps are provided, namely, the space between the members 15, 30 and 35 and the space within the member 45. This minimizes any tendency of smoke or vapor to escape between the opposed bearing faces of the members 35 and 45. Also, when the member 45 is lifted to insert ashes or butts, inasmuch as the bulk of the vapor is in the two traps there is a minimum tendency of vapor or smoke to escape.

With reference, for example, to Figure 3, it will be understood that the member 62 may be screw-threaded or not, as desired. A pin 70 may be provided to serve as additional locking means for preventing unintended withdrawal of the upper tray.

It will be noted also from Figure 5 that the sleeve 27 of the tray 25 is slightly tapered. I do not wish to be limited to a tapered sleeve at this point but there is some advantage in tapering the sleeve as it permits a tight fit between the top of the sleeve 27 and the member 31. The tray can be easily removed, owing to the tapered fit and can be placed on the stand easily without binding and yet there is no tendency of the tray to tilt when it is positioned in a normal position. In other words, it is easier to make a tight tapered fit, with maximum ease of removability, while preventing unintended tilting of the tray.

A further characteristic of my device is that when hot cigarettes are dumped on the member 35, as when the member 47 is lifted, the cigarettes tend to strike the tube 52 and are deflected back away from the central portion of the container so that the vapor and smoke rising from the heated cigarette will tend to pass into the vapor traps above mentioned.

The vertical tube 52 is an important aid in guiding the threaded stem 38 into the tapped hole in the sleeve 14. The bell end on the upper part of the tube 52 provides a grip for the hand, the bell end preventing it from slipping it out of the hand. The funnel end also provides an easy entry for the pointed end 39 of the rod 38.

The shape of the handle 36 is such that it has a tendency to guide the beverage tray 25 into its proper position on the stand. The bearing angle of the part 47, which is preferably machined, forms a valve seat with the part 35 which is so designed that constant use will have a tendency to make the parts fit better. There is an actual improvement with use, as wear tends to form a bearing fit which is increasingly tight. The angles or slopes of the parts 35 and 47 are sufficiently steep to prevent ashes, butts and the like from clinging to the surface. They slide readily down into the container 50. Preferably the grooves 33, supporting the cigar and cigarette butts are sand blasted or otherwise roughened to have a surface much coarser than the surface of the remaining parts. It prevents butts from slipping out of the grooves.

Referring to Figures 2 and 3, it will be understood that whereas I have shown the portions 62 as screwthreaded, a smooth snug fit may be employed and any other suitable locking means may be employed for preventing unintended separation of the parts. I may, for example, employ a transverse pin 70 or a bayonet lock or any other practical means for securing the tray 64 against unintended movement.

I claim:

1. In an ash receiver, a housing, a receptacle removably positioned within said housing, said receptacle having a central upwardly extending tube, a cover for said housing including a downwardly and inwardly inclined hopper the lower aperture of which is vertically aligned with the open top of said receptacle and which depends to a horizontal plane lower than the top of said tube, a handle for said cover, a guide extending downwardly from said handle through said tube and into a lower portion of the housing, a locking connection between said guide and the lower portion of the housing and a closure movable on said guide, said closure being normally gravitationally seated against a lower portion of said housing.

2. In an ash receiver, a housing, a receptacle removably positioned within said housing, said receptacle having a central upwardly extending tube, a cover for said housing including a downwardly and inwardly inclined hopper the lower aperture of which is vertically aligned with the open top of said receptacle and which depends to a horizontal plane lower than the top of said tube, a handle for said cover, a guide extending downwardly from said handle through said tube and into a lower portion of the housing, a locking connection between said guide and the lower portion of the housing and a closure movable on said guide, said closure being normally gravitationally seated against a lower portion of said housing, said closure being provided with a tapered central bore adapted to permit the closure to tilt laterally in relation to said guide and to seat itself in relation to the lower portion of said hopper.

3. In an ash receiver, a housing, a receptacle removably positioned within said housing, a cover for said housing, overlying said receptacle, said cover including a downwardly and inwardly inclined hopper the lower aperture of which is vertically aligned with the open top of said receptacle, and a movable closure for said hopper, adapted to engage the lower portion of said hopper, said closure having a bearing seat opposed to a corresponding seat adjacent the lower edge of said hopper, and a generally vertical guiding means for said movable closure, said closure being tiltably as well as slidably mounted upon said guiding means, whereby said closure is permitted to seat itself in relation to the opposed bearing seat upon the hopper.

4. In an ash receiver, a housing, a receptacle removably positioned within said housing, a cover for said housing, overlying said receptacle, said cover including a downwardly and inwardly inclined hopper the lower aperture of which is vertically aligned with the open top of said receptacle, and a movable closure for said hopper, adapted to engage the lower portion of said hopper, said closure being gravitationally supported upon said hopper, and generally vertical guiding means for said movable closure, upon which said closure is slidably and tiltably mounted.

5. In an ash receiver, a housing, a receptacle removably positioned within said housing, a cover for said housing, overlying said receptacle, said cover including a hopper vertically aligned with the open top of said receptacle, and a movable closure for said hopper, adapted gravitationally to engage said hopper, and generally vertical guiding means for said closure, said closure being slidably and tiltably mounted upon said guiding means and being upwardly manually movable.

therealong, said closure being provided with a hand engaging portion adapted to facilitate such manual movement.

6. In an ash receiver, a housing, a receptacle removably positioned within said housing, a cover for said housing, overlying said receptacle, said cover including a hopper vertically aligned with the open top of said receptacle, and a movable closure for said hopper, adapted gravitationally to engage said hopper, and generally vertical guiding means for said closure, along which said closure may be upwardly manually moved, said closure being upwardly generally conic and at its apex being penetrated by a tapered opening surrounding said vertical guiding means, and increasing downwardly in diameter from a minimum diameter only slightly greater than the diameter of the vertical guiding means, whereby a measure of lateral tilting of the lower portion 20 of said closure is permitted.

7. In an ash receiver, a housing, a receptacle removably positioned within said housing, a cover for said housing, overlying said receptacle, said cover including a hopper vertically aligned with the open top of said receptacle, and a movable closure for said hopper, adapted gravitationally to engage said hopper, and generally vertical guiding means for said closure, along which said closure may be upwardly manually moved, said 25 closure being tiltably as well as slidably mounted upon said guiding means, and a handle for said cover, to which the upper end of said guiding means is secured.

8. In an ash receiver, a housing, a receptacle removably positioned within said housing, a cover for said housing, overlying said receptacle, said cover including a hopper vertically aligned with the open top of said receptacle, and a movable closure for said hopper, adapted gravitationally 30 to engage said hopper, and generally vertical guiding means for said closure, along which said closure may be upwardly manually moved, said closure being tiltably as well as slidably mounted upon said guiding means, and a handle for said cover, to which the upper end of said guiding means is secured, the lower end of said guiding means being adapted to be removably secured to the lower portion of said housing.

9. In an ash receiver, a housing a receptacle removably positioned within said housing, a cover for said housing, overlying said receptacle, said cover including a hopper vertically aligned with the open top of said receptacle, and a movable closure for said hopper, adapted gravitationally 35 to engage said hopper, said closure being hollow the closing connection between the hopper and the closure being at a level substantially below the upper edge of the housing, the space between the hopper and the upper edge of the housing and the space within the movable closure, being of sufficient cubic content, above the level of the intersection between the movable closure and the hopper, to serve as traps for upwardly rising smoke or vapor from the contents of the removable receptacle.

10. In an ash receiver, a base, supporting means extending upwardly from said base, a receptacle secured to the upper end of said supporting means, and a tray surrounding and removably positioned upon said receptacle, said tray having a central aperture through which said receptacle extends, and a sleeve, surrounding and upwardly extending

from said central aperture and adapted for centering contact with said receptacle.

11. In an ash receiver, a base, supporting means extending upwardly from said base, a receptacle secured to the upper end of said supporting means, and a tray surrounding and removably positioned upon said receptacle, said tray having a central aperture through which said receptacle extends, and a sleeve, surrounding and upwardly extending from said central aperture and adapted for centering contact with said receptacle, and a circumferential shelf about said receptacle, adapted to receive and support said tray.

12. In an ash receiver, a base, supporting means extending upwardly from said base, a receptacle secured to the upper end of said supporting means, and a tray surrounding and removably positioned upon said receptacle, said tray having a central aperture through which said receptacle extends, and a supplemental tray of smaller diameter, positioned beneath the first mentioned tray.

• 13. In an ash receiver, a base, supporting means extending upwardly from said base, a receptacle secured to the upper end of said supporting means, and a tray surrounding and removably positioned upon said receptacle, said tray having a central aperture through which said receptacle extends, and a conic sleeve, surrounding and upwardly extending from said central aperture and adapted for centering contact with said receptacle, adjacent the upper and lower portions of said conic sleeve, whereby the sleeve is guided into firm aligning contact with said receptacle.

14. A receptacle having ash receiving aperture, a base for said receptacle, and a tray removably positioned upon said receptacle, said tray being provided with a central conic flange adapted for centering engagement with said receptacle and extending circumferentially about 40 said receptacle when the tray is in position.

15. In an ash receiver, a base, a receptacle positioned above said base, and a tray surrounding and removably positioned upon said receptacle, said tray having a central aperture through which said receptacle extends, and a sleeve, surrounding and extending from said central aperture and adapted for centering contact with said receptacle, said sleeve extending a substantial distance along the opposed portion of said receptacle and out of the plane of the tray, and being of sufficient length to prevent, in cooperation with the opposed portion of the receptacle, any substantial tilting of the tray in relation to said receptacle.

16. In an ash receiver, a base, a receptacle positioned above said base, and a tray surrounding and removably positioned upon said receptacle, said tray having a central aperture through which said receptacle extends, and a sleeve, surrounding and extending from said central aperture and adapted for centering contact with said receptacle, said sleeve extending a substantial distance along the opposed portion of said receptacle and out of the plane of the tray, and being of sufficient length to prevent, in cooperation with the opposed portion of the receptacle, any substantial tilting of the tray in relation to said receptacle, said receptacle being provided with a circumferential ledge member upon which said tray is adapted 70 to seat.

WILLIAM J. CAMPBELL.

DISCLAIMER

2,000,920.—*William J. Campbell*, Indianapolis, Ind. SMOKING STAND. Patent dated May 14, 1935. Disclaimer filed May 28, 1937, by the assignee, *Climax Machinery Company*.

Hereby enters this disclaimer to claims 10 and 11 of said patent.
